CLAIM

The ornamental design for an actuator for aerosol containers, as shown and described.

DESCRIPTION

FIG. 1 is a top front perspective view of an actuator for aerosol containers showing the new design;

FIG. 2 is a top back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a top front perspective view thereof, wherein the actuator is mounted on an aerosol container to show the environment in which the actuator may be used.

The broken lines illustrating an aerosol container depict environment and form no part of the claimed design. All other broken lines depict portions of the actuator for aerosol containers that form no part of the claimed design.
